UNITED STATES PATENT OFFICE.

JOHN SHEPARD, OF PITTSBURGH, PENNSYLVANIA.

RAIL-JOINT.

1,348,244.

Specification of Letters Patent.

Patented Aug. 3, 1920.

Application filed February 28, 1919. Serial No. 279,685.

To all whom it may concern:

Be it known that I, JOHN SHEPARD, a citizen of the United States, residing at Pittsburgh, in the county of Allegheny and State 5 of Pennsylvania, have invented certain new and useful Improvements in Rail-Joints; and I do hereby declare the following to be a full, clear, and exact description of the invention, such as will enable others skilled 10 in the art to which it appertains to make and use the same.

This invention relates to rail joints and the primary object of the invention is to provide an improved means for connecting 15 the terminals of railroad rails together, without the usual nuts and bolts extending through the rails, so as to eliminate the necessity of boring holes through the rail ends and thereby weakening the same.

Another object of the invention is to provide an improved rail joint for preventing 20 the separation of the rail terminals, which is generally caused by displacement of the bolts from the rails, caused by the jar transmitted to the rails from the passing trains.

A still further object of the invention is to provide an improved rail joint, which will allow the rails to contract and expand 25 during the varying weather conditions and at the same time prevent displacement of the rails.

A still further object of the invention is to provide an improved rail chair for receiving the rail ends, which extends from 30 one tie to another, so as to form a bridge for the rail joints and thereby prevent the rails from being forced downwardly by the weight of the train.

A further object of the invention is to provide improved means for connecting the rail 35 chair to the ties, so as to prevent displacement thereof.

A still further object of the invention is to provide an improved rail joint of the above 40 character, which is durable and efficient in use, one that is simple and easy to manufacture, and one that can be placed upon the market at a reasonable cost.

With these and other objects in view, the 45 invention consists in the novel construction, arrangement and formation of parts, as will be hereinafter more specifically described, claimed and illustrated in the accompanying drawings.

Figure 1 is a perspective view of the improved rail joint,

Fig. 2 is a transverse section taken on line 2—2 of Fig. 1, and

Fig. 3 is a transverse sectional view through one of the ties showing a slightly modified form of the invention.

Referring to the drawings in detail, wherein similar reference characters designate corresponding parts throughout the several views, the numeral 1 generally indicates the improved rail chair, which is adapted to receive the terminals of the ordinary rail sections 2 and 3. The rail chair 1 extends across the ordinary ties 4.

The rail chair 1 includes a base plate 5, 70 having inwardly extending flanges 6 formed on the side edges thereof which are adapted to engage over the base flanges 7 of the rail sections 2 and 3. Each of the rail sections includes the head or ball 8, the web 9 and 75 the base flanges 7. The inner surfaces of the inwardly extending flanges 6 are formed, so as to conform to the configuration of the base flanges 7 and to snugly receive the same, so as to prevent lateral movement of the rail 80 sections in the chair. These flanges extend the entire length of the base plate and are provided with extensions 10 at each side thereof, which extend upwardly and engage the web 9 of the rails and the lower surfaces 85 of the heads of the rails. The upper edges of the extensions 10 are inclined and rounded as at 11 to conform to the configuration of the head and extend slightly beyond the side edges of the head and form 90 means for providing an additional support for the heads of the rails. These extensions, as stated, form a brace for the rail heads and also form means for snugly engaging the web and head, so as to form a friction contact with the rail and prevent creeping 95 thereof.

The chair 1 extends from one tie to the adjacent tie, as clearly shown in Fig. 1, and forms a bridge for the rail joint and thus 100 prevents the same from being bent downwardly by the passing trains. The chair 1 is provided with spaced apertures 12, which receive the upper ends of the U-shaped bolts or clevises 13 which preferably extend 105 around the ties 4, as clearly shown in Fig. 1 of the drawings. The legs 14 of the clevises are preferably thickened, as at 16, so as to strengthen the same and prevent the same from being broken. The upper terminals of the clevises are threaded and are extended through a longitudinally extend-

ing plate or washer 17, which has the lower surface thereof beveled as at 18 to conform to the configuration of the flanges. Suitable nuts 19 are fitted on the threaded ends 5 of the bolts and hold the same against displacement. By this construction longitudinal movement of the chair is eliminated. The plate 17 extends from one bolt end to the other so that the same will be prevented 10 from turning and thus helps to prevent displacement of the nuts. The edges of the ties may be provided with grooves for receiving the legs of the clevises so as to prevent lateral movement of the rails and chairs 15 and thus prevent spreading of the rails.

If so desired, the ties may be provided with vertically extending apertures 22 through which the legs of the clevises may be extended and the upper ends thereof may 20 be extended through the base flanges of the rails, as clearly shown in Fig. 3 of the drawings.

It is to be understood that the rail joint can be used either for steam or electric lines 25 and the clevises may be dispensed with entirely and the chair spiked into position.

To prevent the nuts 19 from being jarred off of the bolts or clevises 14, the meeting surfaces of the nuts 19 and the plates 17 30 should be roughened and a mixture of grease and sand placed intermediate the same, which would effectively bind the same together.

In practice, I have found that the form 35 of my invention illustrated in the accompanying drawings and referred to in the above description, as the preferred embodiment, is the most efficient and practical; yet realizing the conditions concurrent with the

adoption of my device will necessarily vary, 40 I desire to emphasize that various minor changes in details of construction, proportion and arrangement of parts may be resorted to, when required without sacrificing any of the advantages of my invention as 45 set forth.

What I claim as new is:

In a device of the class described, the combination with a pair of rail sections and supporting ties therefor, of a rail chair arranged to receive the meeting terminals of the rail sections, flanges formed on the rail chair and arranged to conform to the configuration of the rail sections and to snugly receive the same, said chair having a pair 55 of spaced apertures formed therein, U-shaped bolts embracing the ties and having the terminals thereof extended through the apertures, said terminals being tapered from the intermediate portions of the bolts 60 toward their ends, longitudinally extending plates extending from one bolt to the other and having apertures formed therein and arranged to receive the terminals of the bolts, the lower surfaces of the plates being 65 beveled to bear snugly upon the upper surface of the chair and the upper surfaces of the plates being level to provide holding surfaces, and nuts fitted on the free ends of the bolts to hold the same against 70 displacement.

In testimony whereof I affix my signature in presence of two witnesses.

JOHN SHEPARD.
